Patented Oct. 10, 1922.

UNITED STATES PATENT OFFICE.

JOHN KLEIN, OF CLEVELAND, OHIO.

PARLOR FLOOR LAMP.

Application filed August 24, 1921. Serial No. 495,042.

To all whom it may concern:

Be it known that I, JOHN KLEIN, a citizen of the United States, resident of Cleveland, county of Cuyahoga, and State of Ohio, have 5 invented new and useful Improvements in Parlor Floor Lamps, of which the following is a specification, the principle of the invention being herein explained and the best mode in which I have contemplated applying that principle, so as to distinguish it 10 from other inventions.

This invention relates to parlor floor lamps and has for its object, to provide a pedestal lamp with a floor light enclosed in the base 15 of the pedestal in addition to usual lamps carried at the top of the pedestal, the floor light together with the colored translucent panels of the base, producing an attractive ornamental effect and also providing a dim 20 lighting effect, pleasing and restful to the eye when the main lamp is turned off, lighting the room just sufficiently to enable persons to move about the room without danger of stumbling over furniture so that they can 25 see to turn on the main pedestal lamp when desired, making it unnecessary to use the wall switch on entering the room.

The annexed drawings and the following description set forth in detail certain means 30 embodying my invention, the disclosed means, however, constituting but one of the various mechanical forms in which the principle of the invention may be employed.

In said annexed drawings:

35 Figure 1 is a side elevation of the pedestal floor lamp.

Figure 2 is a sectional plan view of the base looking down from the line II—II of Figure 1.

40 Figure 3 is a sectional view taken on line III—III of Figure 2 looking in the direction indicated by the arrows.

Figure 4 is a plan view of the bottom of the pedestal base.

45 Figure 5 is a side elevation of the pedestal base.

Figure 6 is a wiring diagram of the lamp circuits.

Referring to the annexed drawings, the 50 lamp pedestal comprises a hollow box-like base 1, having colored glass panels 2 and 3 in the side walls thereof and colored glass panels 4 and 5 in the top thereof. The hollow base 1 is supported upon legs 6 and 55 carries centrally of its top a vertical stand-

ard 7. Upon the top of the standard 7 is mounted the usual lamp fixture, comprising the shade 8 and lamp sockets 9 for the incandescent bulbs 10. Associated with the sockets 9 are the usual chain switch members 11.

The bottom 12 of the box base 1 has mounted therein, the lamp socket 13 adapted to receive the small candle power bulb 14 within the box and having a button switch 15 below the bottom 12.

Current is supplied to the pedestal lamps by means of wires 16 leading from the wall plug 17, to the base socket 13 and branch wires 18 leading from the wires 16 through 70 the axial passage 19 in the standard 7 to the main lamp sockets 9 at the top of the standard.

In order to provide convenient access to the interior of the base 1 for insertion or 75 removal of the base bulb, the bottom 12 is provided with a hand opening 20 closed by the removable cover 21.

In the normal use of the parlor lamp herein disclosed, the main lamps 10 as well 80 as the base lamp 14 will be lighted. When the main lamps 10 are lighted, the base lamp 14 is useful merely for ornamental effect. If, however, it is desired to leave the room temporarily, the main lamps 10 can be 85 turned off leaving the base light 14 on. The base light 14 will then provide sufficient light to enable one to return directly to the pedestal instead of leaving the room in total darkness, making it convenient to use the pedestal 90 lamp to the exclusion of other illuminating means, thus economizing in the use of current. The base lamp 14 when used alone provides a pleasing and restful lighting effect, somewhat similar to a fireplace. The 95 base lamp 14 also provides an economical means of lighting rooms not occupied, but through which persons frequently pass.

Having described my invention, what I 100 claim is.

1. A parlor floor lamp comprising a pedestal having a hollow base; a main lamp socket carried by the upper end thereof; a lamp socket having its lamp receiving end within said base; a switch associated with 105 said base lamp socket and located outside said base, and an independent switch associated with said main lamp socket.

2. A parlor floor lamp comprising; a hollow box base; colored translucent panels in 110

the walls of said box base; supporting legs secured to the bottom of said box base; a hand opening having a cover plate in the bottom of said box base; a lamp socket projecting upwardly into said bottom adjacent said opening; a switch on said socket below said bottom; a central standard supported

on said box base; a main lamp fixture supported upon the top of said standard; and an independent switch associated with said fixture.

Signed by me this 1st day of Aug., 1921.

JOHN KLEIN.
